UNITED STATES PATENT OFFICE.

FRANK E. WATTS, OF DETROIT, MICHIGAN, ASSIGNOR TO HUPP MOTOR CAR CORPORATION, OF RICHMOND, VIRGINIA, A CORPORATION OF VIRGINIA.

ENGINE-STARTER.

1,342,478.

Specification of Letters Patent.

Patented June 8, 1920.

Application filed December 14, 1917. Serial No. 207,026.

To all whom it may concern:

Be it known that I, FRANK E. WATTS, a citizen of the United States of America, residing at Detroit, in the county of Wayne 5 and State of Michigan, have invented certain new and useful Improvements in Engine-Starters, of which the following is a specification, reference being had therein to the accompanying drawings.

10 The invention relates to engine starters and has particular reference to the construction by means of which the starting motor may be conveniently mounted in relation to the engine casing. To this end the invention 15 comprises the novel construction as hereinafter set forth.

In the drawings:

Figure 1 is a plan view of a portion of the engine casing including the housing for 20 the transmission gearing;

Fig. 2 is an end elevation thereof.

In the construction of power units for motor vehicles it is usual to mount the starter on some portion of the engine casing 25 ing so as to maintain the same in fixed relation to the mechanism which is driven in starting. Where the driven member is on the fly-wheel, which is usually associated with the clutch and transmission mechanism, the starting motor must be mounted 30 in relation to these parts. With the present construction I have devised a simple mounting and one in which the starting motor is accessibly positioned, by forming a flange on 35 the housing for the transmission and fly-wheel and bolting the motor thereto. This has the advantage that the face of the flange on which the motor is mounted may be conveniently machined at the same time that 40 the housing is set for the performance of other machining operations thereon.

In detail, A is the engine housing and B is the housing for the transmission gearing which is secured to the housing A by the 45 flange C apertured at D for clamping bolts.

The housing B is fashioned to receive the fly-wheel E, which as shown is provided with a peripheral gear F for engaging the pinion G of the starting motor H. The mounting for this motor is formed by an 50 extension I at one point in the flange C, which forms a bearing for the end flange J of the starting motor case, said flange being apertured to register with apertures in the flange I and secured thereto by bolts K. 55 Where the housing B is thus secured the driving shaft of the starting motor will extend parallel to the axis of the main crank-shaft and adjacent to the gear F, so that the pinion G may be moved into or out of mesh 60 with the gear by sliding longitudinally on said shaft. The shaft and pinion will be housed in a portion of the housing B for the transmission gearing.

The construction being as described, the 65 starting motor may be mounted or disengaged by the simple operation of securing or loosening the bolts K, and when mounted it is securely fastened in fixed relation to the fly-wheel and gear-wheel F. 70

What I claim as my invention is:

1. In an engine, the combination with the engine casing and an adjacent casing for housing a fly-wheel and transmission gearing, of a flange on the latter casing for securing the same to the engine casing, and a starting motor mounted on an extension of 75 said flange.

2. The combination with an engine casing and an adjacent casing for housing the fly-wheel and transmission gearing, of a flange on the latter casing for securing the same to the engine casing provided with an extension at one point, a starting motor having a flanged end mounted on the extended 80 flange of said housing, and means for securing said starting motor to said flange. 85

In testimony whereof I affix my signature.

FRANK E. WATTS.
